UNITED STATES PATENT OFFICE.

LOUIS WELKER, SR., OF WILLIAMSPORT, PENNSYLVANIA.

TABLE.

SPECIFICATION forming part of Letters Patent No. 733,925, dated July 14, 1903.

Application filed January 13, 1902. Serial No. 89,580. (No model.)

To all whom it may concern:

Be it known that I, LOUIS WELKER, Sr., a resident of Williamsport, in the county of Lycoming and State of Pennsylvania, have invented certain new and useful Improvements in Tables; and I do hereby declare the following to be a full, clear, and exact description of the invention, such as will enable others skilled in the art to which it appertains to make and use the same.

My invention relates to an improvement in tables, the object of the invention being to provide simple and efficient means for connecting the members of a divided pillar to the table-top sections in such manner as to prevent said members of the divided pillar from sagging and to enable the ready adjustment of the pillar-sections without danger of forcing the pillar out of its proper vertical position.

With this object in view the invention consists in certain novel features of construction and combinations and arrangements of parts, as will be more fully hereinafter described, and pointed out in the claims.

In the accompanying drawings, Figure 1 is a view in elevation, partly in section, illustrating my improvement. Fig. 2 is a bottom plan view showing the central pillar in section, and Fig. 3 is an enlarged view of brace 11 detached.

1 represents the central supporting pillar or standard, which is made in the form of two independent sections, each having diverging feet 2 at their lower ends to support the table in proper position. On the upper ends of these pillar-sections bridges 3 are rigidly secured, and the latter are secured to the lower faces of the top sections 4 at their meeting edges. The top sections are preferably provided with the ordinary depending rim 5 and are secured on slides 6 of any approved construction located at the ends of bridges 3. A central-leg bridge 7 is secured at its respective ends to two of the slides and is secured between its ends on a center leg 8, inclosed within the pillar when the table is contracted, and to permit the sections of the pillar to come snugly together they are notched or grooved, as shown at 9, to receive

center-leg bridge 7, as clearly shown in the accompanying drawings. In all tables of this character heretofore made the pillar-sections

have a tendency to and, in fact, do become sprung apart at their lower ends, and to prevent this and to remedy the same if it should occur I provide braces 10 and 11, as will now be explained.

The brace 10 consists of a metal bar perforated at its ends to receive rivets or bolts 12 and pivotally secure the respective ends of the bar between parallel lugs or ears 13 on brackets 14, one of which is secured to one table-top section and the other to a section of the pillar 1, the pivotal connection of the bar with the brackets enabling the bar to be secured at any angle desired and to any point on the pillar however irregular the surface thereof may be.

The brace 11 is constructed precisely like brace 10, except that it is made in two sections connected by a turnbuckle 15 to permit adjustment of the brace longitudinally to force the pillar-sections together when sprung apart and also to secure just the proper tension of the braces on the pillar-sections to maintain them rigid.

I might of course employ two adjustable braces, if desired; but I prefer to employ only one, for the reason that with but one adjustable brace there is no possibility of an inexperienced person's forcing the pillar out of a vertical position, while with two adjustable braces this is liable to occur, to the great injury of the table.

A great many slight changes might be resorted to in the general form and arrangement of the several parts described without departing from the spirit and scope of my invention, and hence I would have it understood that I do not wish to limit myself to the precise details set forth, but consider myself at liberty to make such slight changes and alterations as fairly fall within the spirit and scope of my invention.

Having fully described my invention, what I claim as new, and desire to secure by Letters Patent, is—

1. In a table, the combination with a divided table-top and a divided central pillar, of braces, each attached at one end to a section of the pillar and at the other end to one of the table-top sections.
2. In a table, the combination with a central pillar comprising two sections movable

- relatively to each other, and a table-top comprising two sections secured respectively to the pillar-sections, of a brace connecting each top section with a pillar-section.
- 5 3. In a table, the combination with a pillar comprising two sections movable relatively to each other, and a top comprising two sections secured to the respective pillar-sections, of a brace connecting each pillar-section with the top section secured thereto, said braces being pivotally connected with the pillar and top sections.
4. In a table, the combination with a pillar comprising two sections movable relatively to

each other and a top comprising two sections secured to the respective pillar-sections, of braces connecting the pillar-sections and the top sections secured thereto, one of said braces comprising longitudinally - adjustable sections. 15

In testimony whereof I have signed this specification in the presence of two subscribing witnesses. 20
